United States Patent Office

Des. 185,273
Patented May 26, 1959

185,273

NEEDLEWORK CARD

Roy L. Flannery, Chicago, Ill., assignor to The Boye
Needle Company, Chicago, Ill., a corporation of Illinois

Application February 2, 1956, Serial No. 40,011

Term of patent 14 years

(Cl. D3—19)

Fig. 1 is a perspective view of a needlework card showing my new design;

Fig. 2 is a top edge view;

Fig. 3 is a top plan view; and

Fig. 4 is a side view in elevation.

The broken line illustration of the needles is for illustrative purposes only.

I claim:

The ornamental design for a needlework card, as shown and described.
